UNITED STATES PATENT OFFICE.

AUGUSTUS FANEUFF, OF TROY, NEW YORK.

CAR-BRAKE.

SPECIFICATION forming part of Letters Patent No. 369,847, dated September 13, 1887.

Application filed April 27, 1887. Serial No. 236,310. (No model.)

To all whom it may concern:

Be it known that I, AUGUSTUS FANEUFF, of Troy, in the county of Rensselaer and State of New York, have invented new and useful 5 Improvements in Car-Brakes, of which the following is a specification.

My invention relates to improvements in car-brakes which are preferably applicable to cars for street-railways, but which can be 10 applied to passenger and freight cars of steam-railroads; and the object of my invention is to provide a simple and effective device for the purposes above set forth. This object I attain by the mechanism illustrated in the accompanying 15 drawings, which is herein referred to and forms part of this specification, and in which—

Figure 1 is a side elevation of a platform-car provided with my invention, showing the 20 brake-shoes out of contact with the car-wheels; Fig. 2, a like elevation showing the brake-shoes in contact with the car-wheels; Fig. 3, an inverted plan view, and Fig. 4 a side elevation, of part of a car, showing a modification 25 of my invention as adapted to operating the brake mechanism at or near the middle of the car.

As represented in the drawings, A is the floor or platform of a car, which may be constructed 30 in any preferred form and manner, and B the car-wheels secured to the axles b, which are fitted to revolve in the boxes C; D, brake-levers, which are bifurcated and spread laterally to be fulcrumed in hangers E, which are in 35 proximity to the car-wheels B. The inner end of said levers are brought nearly together at a point that is near the center of the floor of the car and intermediate to the car-axles b. The outer ends of said brake-levers are made 40 in the form of cranks d, to which the brake-shoes F are pivoted.

The contiguous inner ends of the brake-levers D are connected by links G to a shackle, H, so that both of said levers will have a simultaneous movement, and each of said levers is connected to separate weights I by chains J, which pass over sheaves j, (shown in dotted lines in the drawings,) the said weights being fitted to slide with perfect freedom on guides 45 K. By this arrangement the inner ends of the brake-levers D will be normally held by the action of the weights I at the highest point of

their movement, and thereby the brake-shoes F will be held out of contact with the car-wheels B.

At each end of the platform A a foot-piece, L, is fitted to slide easily in a guide, M, and each foot-piece is connected to the shackle H by a chain, N, that is carried over guide-sheaves n, as shown in Figs. 1 and 2.

My invention as just described can be operated from either end of the car, and its operation is as follows: The brake-shoes F being out of contact with the car-wheels B, as shown in Fig. 1, to apply the brakes it is necessary 55 to apply the pressure of the foot-piece L to depress the latter, as shown in Fig. 2, and thereby the chain N, that is connected to the depressed foot-piece, is drawn down to produce a corresponding movement of the shackle H and the 60 inner ends of the brake-levers D, whereby the cranks d are moved to bring the brake-shoes F into frictional contact with the car-wheels B. Simultaneously with the movements just described the weights I are drawn up to the 65 highest point of their movement. On the release of the foot-piece L from the applied pressure the weights I will raise the inner ends 70 of the brake-levers D to their normal position, thereby releasing the brake-shoes F from contact with the car-wheels B, and the foot-piece L will be carried by the chain N back to its 75 former position.

When preferred, the usual vertical shafts with hand-cranks, or the ordinary operating 80 levers, may be substituted for the sliding foot-pieces L as a means for operating my brake mechanism.

In the modification shown in Fig. 4 the foot-pieces L at the ends of the car are dispensed with. A foot-presser, L', is connected directly to the shackle H, and by depressing said foot-presser, the inner ends of the brake-levers D are forced downward to operate the brake-shoes F, in the manner hereinabove described. 90 This last-described form of my brake mechanism is especially designed for use on cable railways, and when so used the foot-presser L' should be located in easy reach of the grip-man, who can then have both hands at liberty 95 for operating the grip-levers.

I claim as my invention—

1. In a car-brake, the combination, with the brake-levers D, whose inner ends are connected

to a shackle, H, and whose outer ends are provided with cranks d, to which the brake-shoes F are pivoted, and the weights I, fitted to slide on guides K, and connected by chains J to the inner end of the brake-levers D, of the foot-pieces L, connected to the shackle H by chains N, all constructed and arranged to operate as and for the purpose herein specified.

2. In a car-brake, the combination, with the 10 brake-levers D, whose inner ends are connected to a shackle, H, and whose outer ends are pro-

vided with cranks d, to which the brake-shoes F are pivoted, and the weights I, fitted to slide on guides K, and connected by chains J to the inner ends of the brake-levers D, of a foot-piece or presser connected to the shackle H, as and for the purpose herein specified. 15

AUGUSTUS FANEUFF.
